UNITED STATES PATENT OFFICE.

CLAUDE GALLICE, OF LOS ANGELES, CALIFORNIA.

DESIGN FOR AN AUTOMOBILE SIGNAL CASING.

Application filed June 6, 1925. Serial No. 13,695. Term of patent 7 years.

To all whom it may concern:

Be it known that I, CLAUDE GALLICE, a citizen of the United States, and a resident of Los Angeles, Los Angeles County, California, have invented a new, original, and ornamental Design for Automobile Signal Casing, of which the following is a specification, reference being had to the accompanying drawing, forming a part thereof.

The figure is a perspective view of an automobile signal showing my new design.

I claim:

The ornamental design for an automobile signal casing, as shown.

Los Angeles, California, May 29th, 1925.

CLAUDE GALLICE.
